DISPLAY RACK

Robert N. Colombe, 207 E. Grand,
Tonkawa, Okla. 74653
Filed May 1, 1967, Ser. No. 634,973
8 Claims. (Cl. 211—165)

ABSTRACT OF THE DISCLOSURE

A display rack including a base having an angulated stem swivelly secured at one of its ends to the base and extending vertically therefrom. A horizontally extending upper end portion of the stem is secured to the center of a substantially horizontal arcuate bar. A plurality of elongated supporting arms are swivelly secured to the bar at horizontally spaced points along the bar and extend outwardly from the bar in a horizontal direction. The outer end of each of the arms is formed as a hook upon which document clips may be hung.

Background of the invention

This invention relates to display racks, and more particularly, the invention relates to a display rack which can be employed for providing concurrent visual exposure of the front and back surfaces of a number of substantially monoplanar papers upon which data or other indicia are scribed.

Brief description of the prior art

A number of types of display racks have been devised for the purpose of displaying commodities or materials of various types in order to permit a more comprehensive and accessible visual inspection to be made of all or certain portions of the displayed articles. In many of these devices, a plurality of horizontally extending swivelly mounted arms are provided in the apparatus with the articles or devices to be displayed suspended from the horizontally extending arms so that, as the arms are swivelled from one position to another, the articles may be sequentially viewed. As an example of the type of prior devices which have been contrived for this purpose, Hansen United States Patent 1,697,866 may be cited. The Hansen patent is directed to a display rack structure which is suited for displaying various types of fabrics and textile products. As has been indicated, the method of operation of display racks of this type is to swivel the article supporting rods apart from each other (in a divergent orientation) so as to expose the article suspended on one of the rods when it is desired to view this particular single article.

A problem which has characterized display racks of the type shown in the Hansen patent, and many others operating on the same general principle, is that the articles which are to be displayed to visual inspection can frequently only be viewed singly, rather than a plurality of the articles being viewed simultaneously in their entirety. A portion of this difficulty arises from the fact that the points of pivotal attachment of the supporting rods used in this type of rack are frequently relatively close to each other with the result that the articles suspended on the rods are necessarily also close to each other, and it is difficult to obtain concurrent spacing of some of the articles from each other to permit them all to be viewed in their entirety at the same time.

Another problem with many types of display racks hereinbefore in use is that the method by which the articles are to be displayed or supported upon the rack prevents the articles from being freely turned in such a way that both the front, back, and side surfaces of the article may be exposed without complete detachment of

2

the article from the rack and relocation on the supporting members. While with some types of articles this does not present any significant impediment to useful employment of the display rack, the described limitation renders such display racks unsuited for certain tasks where both a front and back surface of the article must be readily accessible to visual observation. For example, there are numerous occasions where a statistician, accountant, or tax attorney, in order to work efficiently and expeditiously, must have ready visual access to a number of forms and to the data which is usually carried on both sides of such forms. The display racks which have been heretofore contrived have not been constructed with the objective of displaying paperwork of this sort, and consequently they have been ill-suited to this use.

Brief description of the present invention

The present invention provides an improved display rack which is especially well adapted for supporting a number of data-carrying, substantially monoplanar documents in an accessible and visually exposed position so that the transcription of data from such documents to other documents may be easily and quickly accomplished. The display rack of the invention is especially useful for the purpose of copying data from the front and back sides of several monoplanar sheets of paper where it is necessary to intermittently refer to the data carried by different ones of the sheets.

Broadly described, the present invention comprises a base having a vertically extending stem swivelly mounted therein. The stem is angulated intermediate its length so that an upper end portion of the stem extends substantially horizontally. A horizontally extending arcuate bar is secured to the upper end of the stem and supports a plurality of cantilevered support arms which extend horizontally from the arcuate bar and are swivelly attached thereto. The free outer ends of the support arms carry U-shaped hood portions which can be used to engage clips or clamps from which data-carrying documents are suspended.

An important object of the invention is to provide an improved display rack which is especially well adapted for displaying substantially monoplanar data-carrying articles such as legal documents.

Another object of the invention is to provide a display rack which can be used to simultaneously display a plurality of data-carrying sheets of paper to permit the data to be quickly and easily transcribed therefrom.

An additional object of the invention is to provide a document display device which can be utilized to permit data printed on the front and back of sheet documents to be quickly and easily subjected to visual scrutiny.

Another object of the invention is to provide an improved document display rack which can be economically constructed and is characterized in having a long and trouble-free operating life.

Additional objects and advantages of the invention will become apparent as the following detailed description is read in conjunction with the accompanying drawings.

Brief description of the drawings

FIGURE 1 is a view in elevation of a display rack constructed in accordance with the present invention as the rack appears when viewed from the front.

FIGURE 2 is a side elevation view of the display rack depicted in FIGURE 1.

FIGURE 3 is a plan view of the display rack depicted in FIGURE 1.

FIGURE 4 is a sectional view taken along line 4—4 of FIGURE 3.

FIGURE 5 is a sectional view taken along line 5—5 of FIGURE 2.

FIGURE 6 is a sectional view taken along line 6—6 of FIGURE 5.

Description of preferred embodiments

In the drawings, the display rack of the present invention includes a base 10 which is generally circular in configuration, and which preferably is formed to include a plurality of recesses or wells 12 in the upper surface thereof for accommodating articles such as paper clips, document clamps, and the like. These are used in conjunction with the display rack as hereinafter described. The base 10 is provided with a lower surface 14 which is configured to permit the base to be rested upon a flat supporting surface, such as a table top or the like. Extending through the center of the base 10 from the upper to the lower side thereof is a stem-receiving aperture 16 which receives the lower end of an elongated, vertically extending stem 18. The stem 18 is swivelly mounted in the base by means of cotter keys 20 and washers 22, or any other suitable means. The stem is thus able to rotate about its axis through an angle of 360°. The upper portion 18b of the stem 18 is bent through an angle of about 90°, and the free upper end of the stem is secured to an arcuate bar 24 at approximately the midpoint of the bar. The horizontally extending upper portion 18b of the stem 18 is preferably of a length such that the arcuate bar 24 is not positioned above the base 10, but rather lies outside the vertical projection of the base (see FIGURE 3).

A plurality of elongated supporting arms 26 which are made of a flexible and resilient material, such as spring metal, are secured at one end to the arcuate bar 24 with the points of securement of the arms to the bar 24 being spaced horizontally from each other over the length of the bar. Each of the arms 26 is secured to the bar 24 by passing a vertically extending end portion 27 of the arm through an aperture 28 formed in the bar, and spreading or flaring the tip 29 of the arm so that the respective arm cannot be removed from its respective aperture in the bar. In this way, each of the arms 26 can swivel about a vertical axis. Immediately adjacent to the end portion of each of the arms 26 which passes through an aperture 28 in the bar 24, each arm is provided with a spring loop 30 which functions to permit each arm to more easily recover its substantially horizontally extending status after it has been bent from this position by the imposition of a weight on the outer end of the arm. The spring loop 30 also functions as a spacing element to space the horizontally extending portion of the arm 26 above the bar 24 and thus permit greater freedom of movement of the arm. At its outer end, each of the arms 26 carries a generally U-shaped hook portion 32, and it will be noted that the plane occupied by each of the U-shaped hook portions extends at an angle of about 45° with respect to a vertical plane containing the arm 26 to which the respective hook portion is connected. It will further be noted that those arms 26 adjacent one end of the bar 24 have their hook portions 32 inclined in the opposite direction from the direction of inclination of the hook portion of the arms on the other end portion of the bar.

In the use of the display rack of the invention, a clip or clamp 34 for holding generally monoplanar sheets of paper or documents is hung or suspended from each of the hook portions 32 of the arms 26. The document can then be clamped in the clamp or clip 34 and will hang downwardly therefrom. The rack can accommodate a great number of such documents, and in each case, data or indicia scribed on one or both sides of each document can be clearly and easily read by one who has need to refer to such data or indicia. By reason of the angulation of the U-shaped hook portions 32 on each arm 28 with respect to the arm, documents which are displayed on the rack from a clamp 34 hung on these hook portions can be easily pivoted about the points where their respective clips or clamps contact the hook portions so as to alternately

expose any portion of the document which it is desired to view. To the end of permitting the most universal movement of the documents, the clamps 34 are preferably of the type having spring biased, normally closed jaws 36 and an apertured handle portion 38 having an aperture therethrough which is sufficiently large to loosely receive the respective hook portion 32. It will also be noted that the attachment of the arms 28 to a relatively long arcuate bar 24 provides relatively good spacing between all parts of the several arms, and thus obviates the difficulty which has been experienced with many types of display racks previously in use of encountering obscurement of many of the documents at such time as it is desired to view a particular one of them. In other words, in the use of the rack of the present invention, several of the documents may be exposed to view simultaneously. This feature provides a marked advantage in using the rack for assisting the work of statisticians, accountants, and other persons in transcribing figures and data from one document to another.

Although a preferred embodiment of the invention has been herein described in order to provide an example of its construction and manner of use which will enable one skilled in the art to practice the invention, it will be readily perceived that many changes and innovations can be made in the described and depicted structure without departure from the basic principles which underlie the invention. All changes and innovations of this type are therefore deemed to be circumscribed by the spirit and scope of the invention except as the same may be necessarily limited by the appended claims or reasonable equivalents thereof.

What is claimed is:

1. A display rack comprising:

a base;
an angulated, elongated stem extending vertically from the base and swivelly mounted in the base, said stem including a vertically extending portion and a horizontally extending upper portion;
a horizontally extending arcuate bar secured to the upper end of the stem; and
a plurality of substantially horizontally extending support arms each pivotally mounted at one end to said bar and each having a generally U-shaped hook portion at its other end for engaging clips for supporting substantially monoplanar documents or the like, said support arms being pivotally secured to said support arm at points spaced from each other therealong.

2. A display rack as defined in claim 1 wherein each of said arms is constructed of spring metal and includes a spring loop, a vertically extending portion extending through said bar and a horizontally extending portion spaced from said vertically extending portion by said spring loop and extending between said spring loop and said U-shaped hook portion whereby each of said arms can swing across said arcuate bar.

3. A display rack as defined in claim 1 wherein said base is provided with a plurality of wells in its upper surface for accommodating clips and the like.

4. A display rack as defined in claim 1 wherein said arcuate bar is positioned outside said base when said base is vertically projected.

5. A display rack as defined in claim 1 wherein said generally U-shaped hook portion of each arm lies in a plane which extends at an angle of about 45° with respect to a vertically extending plane containing the remainder of the respective arm.

6. A display rack as defined in claim 1 further characterized to include at least one clamp detachably engaged by the hook portion of at least one of said arms, said clamp having spring-biased, normally closed jaws and an apertured handle portion, the aperture in said handle portion loosely receiving said hook portion whereby said clamps can each be pivoted in universal movement on the respective hook portions.

7. A display rack as defined in claim 5 wherein said arcuate bar is positioned outside said base when said base is vertically projected.

8. A display rack as defined in claim 7 wherein each of said arms is constructed of spring metal and includes a spring loop, a vertically extending portion extending through said bar and a horizontally extending portion spaced from said vertically extending portion by said spring loop and extending between said spring loop and said U-shaped hook portion.
